(57) CLAIM

The ornamental design for a “drinking vessel with a lid,” as shown and described.

DESCRIPTION

FIG. 1 is a front, right side perspective view of a drinking vessel with a lid showing our new design;

FIG. 2 is an enlarged top view thereof;

FIG. 3 is an enlarged bottom view thereof;

FIG. 4 is a right side view thereof;

FIG. 5 is a left side view thereof;

FIG. 6 is a front view thereof; and,

FIG. 7 is a rear view thereof.

The broken lines are shown for the purpose of illustrating parts of the article that form no part of the claim.
